UNITED STATES PATENT OFFICE.

CARL G. SWEBILIUS, OF NEW HAVEN, CONNECTICUT, ASSIGNOR TO THE MARLIN FIREARMS CORPORATION, OF NEW HAVEN, CONNECTICUT, A CORPORATION OF DELAWARE.

REPEATING FIREARM.

Application filed July 18, 1923, Serial No. 652,387. Renewed November 17, 1925.

This invention relates to firearms and more particularly to take-down repeating firearms having tubular magazines.

The objects of this invention are to feed cartridges simply and efficiently from the magazine to the cartridge chamber, to improve the means for loading the magazine and locking the trigger in safety, and to prevent accidental release of the take-down bolt.

These objects are attained by pivotally attaching to the breech bolt a cartridge carrier having a portion adapted to engage a cartridge entering from the magazine.

Means are provided to tilt the carrier during the rearward movement of the breech bolt to lift the cartridge into alignment with the cartridge chamber. The safety lock comprises a pivoted member having a portion adapted to directly engage the trigger. The magazine comprises a slotted tubular member surrounded by a sliding slotted sleeve. A cartridge follower is mounted in the tubular member and is provided with a pawl adapted to project through the slot. On the sleeve is provided means to engage said pawl to move the follower when the sleeve is moved to allow loading of the magazine. Engaging one end of the take-down bolt is a spring operated latch to maintain the bolt in operative position.

Referring now to the drawings, Fig. 1 is a side elevation partially in section of a gun embodying the invention, with the breech closed, and Fig. 2 is a similar view with the breech open. Fig. 3 is a section of the magazine and Fig. 4 is a front elevation of the breech bolt.

A receiver 10 supports a barrel 11 from its front wall. A breech bolt 12 is reciprocatively mounted in the receiver and is operated by the forearm 13 through the medium of the action rod 14. A locking bolt 15 which seats in the socket 16 in the top wall 45 of the receiver maintains the breech bolt in breech closing position. The locking bolt, breech bolt and action rod are associated in the manner disclosed in the patent to Swebilius et al. No. 1,110,837, granted September 15, 1914, so that when the breech bolt is in breech closing position, the locking bolt is moved into or out of locking position by a slight forward or rearward movement of the action rod.

A sear 17 is slidably and pivotally

mounted in the receiver and has a portion 18 cooperating with the action rod and a lug 19 cooperating with a shoulder 20 on the hammer 21 to prevent unbreeching of the gun until after the hammer has fallen and 60 to prevent the release of the hammer until after the gun is completely breeched all according to the disclosure in the aforementioned patent. A hammer spring 22 provides the driving force for the hammer 21 and a trigger 23 engages a shoulder 24 on the hammer to hold the latter in cocked position.

A cartridge carrier 25 is pivotally mounted in a socket in the under-portion of the breech bolt and has a hook portion 26 at its forward end. In the front wall of the breech bolt is a groove 27 which decreases in depth from the bottom to the top of the breech bolt. This groove is adapted 75 to receive the head of a cartridge and act as a guide for the cartridge. A tubular magazine is carried by the receiver and barrel and is arranged to deliver cartridges in position to be engaged by the hook 26. At 80 the rear of the carrier is a portion 29 adapted to engage the base of the locking bolt 15 and another portion 30 adapted to engage the lug 19 on the sear 17 during the reciprocation of the breech bolt incident to 85 reloading the gun.

In the trigger 23 is cut a socket 32 in which is adapted to seat a shoulder of the safety lock 33 which is pivotally mounted in a slot in the trigger guard 34. A spring 90 35 maintains the trigger in or out of trigger engaging position. The member 33 is so positioned that it may be easily operated by the hand grasping the stock of the gun.

The magazine comprises a slotted tube 36 95 having one end fitting in an aperture in the front wall of the receiver, the upper wall of the aperture being oblique upwardly. A plug 37 in the other end of the tube 36 is attached to the barrel by the screw 38. An 100 aperture 39 is provided for inserting cartridges into the tube 36. A slotted sleeve 40 is slidably mounted on the tube 36. A cartridge follower 41 is mounted in the tube 36 and a pawl 42, provided with a lug having 105 an oblique surface, is pivoted in a slot in the follower and projects through the slot in tube 36. Interposed between the plug 37 and the follower 41 is a spring 43. In one end of the sleeve 40 is a slot 44 into which 110

the pawl lug may project. In the plug 37 is a spring pressed plunger 45 which is adapted to project through either of the apertures 46 or 47 in the sleeve 40 to hold it 5 in either of its positions.

To load this gun, the plunger 45 is pressed in to release the sleeve 40 and the latter is pulled out until the plunger projects through the aperture 47. The follower is 10 pulled forward of the magazine against the action of the spring 43 by virtue of the engagement of the lug of pawl 42 with the wall of the slot 44. The cartridges are then inserted through the aperture 39. When the 15 cartridges have been inserted, the plunger 45 is again pressed in thus releasing the sleeve 40. The latter will be moved under the influence of spring 43 until the follower 41 reaches the cartridges. It is then pushed 20 manually toward the receiver until the plunger 45 projects through the aperture 46. During this movement, the pawl 42 is forced inwardly by virtue of the oblique surface of the pawl lug and remains in this position 25 until all the cartridges have been fed from the magazine when it will again project through the slot 44.

The receiver 10 is open at the bottom and rear and is provided near its front wall with 30 a pin 49 extending between the side walls. The stock 50 of the gun carries a projecting tang 51 having on its end a hook 52 adapted to engage the pin 49. In the upper wall of the receiver is a slot 53 into which is adapted 35 to seat the head of a bolt 54 slidably mounted in the stock to effect a locking connection therebetween when the hook 52 is engaged with the pin 49. A spring 55 normally 40 presses the bolt into operative position and a lever 56 is pivoted to the stock and passes through the bolt to a button 57 on the stock. By means of this lever and button, the bolt 45 may be retracted. A spring pressed latch 58 is pivoted to the stock 50 and is adapted to engage one end of the button 57 to prevent 50 retraction of the bolt. When, however, it is desired to retract the bolt, the latch is depressed and the button slid back over the latch. Accidental retraction of the bolt is thus prevented. The bolt may be one piece or may be of the adjustable type disclosed in the patent to C. G. Swebilius 1,412,208 of April 11, 1922.

The cartridges are fed from the magazine to the chamber as follows: On the breeching of the gun, a cartridge is released from the magazine in the usual manner and is forced against the bottom of the groove 27 in the breech-bolt by action of the spring 43. In this position, the hook 26 of the carrier underlies the rear end of the cartridge. As the action rod 14 is pulled back, it first pulls down the locking bolt 15 which engages the portion 29 of the carrier 25 thus 65 bringing the hook 26 into engagement with

the cartridge to tilt it, as shown in Fig. 1, thus insuring a firm grip on the cartridge before the breech-bolt starts to move rearwardly. As the breech-bolt moves rearwardly, the hook 26 holds the cartridge in 70 the groove 27. Near the end of the rear stroke of the breech bolt, the portion 30 of the carrier 25 engages the lug 19, thereby causing the carrier to assume the position shown in Fig. 2. The tilting of the carrier moves the cartridge up to the top of the groove where it is grasped by the spring members or extractors 47. As the breech-bolt moves forward, the portion 30 of the carrier moves in a groove 48 in the bottom 80 of the receiver. As it strikes the front wall of groove 48, the carrier is tilted part way until the portion 29 engages the locking bolt 15. As the breech-bolt moves forward, the hook 26 of the carrier engages the next cartridge in the magazine and pushes all the cartridges in magazine forward slightly. As the locking bolt moves up into locking 85 position, the carrier is tilted further downward, and allows the engaged cartridge to slide over it against the breech-bolt, by the pressure of the cartridges in the magazine. 90

It is, of course, understood that various modifications may be made in the structure of this firearm without in any manner departing from the spirit of the invention as 95 defined in the appended claims.

What is claimed is:

1. In a firearm, a receiver, a breech-bolt slidably mounted therein, a magazine, a member pivoted to said breech bolt to underlie a cartridge released from the magazine, and means to tilt said pivoted member. 100
2. In a firearm, a receiver, a breech bolt slidably mounted therein, a magazine, a member pivoted to said breech bolt to underlie a cartridge released from the magazine, and means to tilt said member during reciprocation of said breech-bolt. 105
3. In a firearm, a receiver, a breech-bolt slidably mounted therein, a magazine, a member pivoted to said breech bolt to underlie a cartridge released from the magazine, and means to engage said member during the rearward stroke of said breech bolt to tilt 110 said member.
4. In a firearm, a receiver, a breech bolt slidably mounted therein, a magazine, a member pivoted to said breech bolt to underlie a cartridge released from the magazine, means to engage said member during the rearward stroke of said breech bolt to tilt 115 said member, and means to return said member to normal position during the forward stroke of said breech-bolt. 120

5. In a firearm, a receiver, a breech-bolt slidably mounted therein, a magazine, a member pivoted to said breech bolt to underlie a cartridge released from the magazine, cartridge guiding means on said breech bolt, 130

- means for feeding a cartridge into operative relation to said guiding means and member, and means to tilt said member during the reciprocation of said breech bolt.
- 5 6. In a firearm, a receiver, a breech bolt slidably mounted therein, a magazine, a member pivoted to said breech bolt to underlie a cartridge released from the magazine, cartridge guiding means on said breech bolt, 70 means for feeding a cartridge into operative relation to said guiding means and member, and means to engage a portion of said member during the rearward stroke of the breech-bolt to tilt said member.
- 10 7. In a firearm, a receiver, a breech-bolt slidably mounted therein, a magazine, a member pivoted to said breech bolt to underlie a cartridge released from the magazine, cartridge guiding means on said breech-bolt, 75 means for feeding a cartridge into operative relation to said guiding means and member, means to engage a portion of said member during the rearward stroke of the breech-bolt to tilt said member, and means to return said member to normal position during the forward stroke of said breech-bolt.
- 15 8. In a firearm, a receiver, a breech-bolt slidably mounted therein, a locking member mounted on said breech-bolt, a cartridge carrier pivotally attached to said breech-bolt, and a lug on said carrier adapted to be engaged by said locking member to move said carrier into cartridge engaging position.
- 20 9. In a firearm, a receiver, a breech-bolt slidably mounted therein, a locking member mounted in said breech-bolt, a cartridge carrier pivotally attached to said breech-bolt, a part of said carrier being adapted to be engaged by said locking member to move said carrier into cartridge engaging position, and means to rock said carrier during reciprocation of breech-bolt.
- 25 10. In a firearm, a receiver, a breech-bolt slidably mounted therein, a locking member mounted on said breech-bolt, a cartridge carrier pivotally attached to said breech-bolt, a lug on said carrier adapted to be engaged by said locking member to move said carrier into cartridge engaging position, and means adapted to be engaged by a portion of said carrier during the rearward stroke of the breech-bolt to tilt said carrier.
- 30 11. In a firearm, a receiver, a breech-bolt slidably mounted therein, a locking member mounted on said breech-bolt, a cartridge carrier pivotally attached to said breech-bolt, a lug on said carrier adapted to be engaged by said locking member to move said carrier into cartridge engaging position, means adapted to be engaged by a portion of said carrier during the rearward stroke of the breech-bolt to tilt said carrier, and means to return said carrier to normal position during the forward stroke of said breech-bolt.
- 35 12. In a firearm, a slotted tubular magazine, a cartridge follower therein, and abutment in said magazine, a spring between said abutment and said follower, a pawl carried by said follower and adapted to project through said slot, a sleeve surrounding said tubular member and slidable thereon, and means on said sleeve to engage said pawl.
- 40 13. In a firearm, a slotted tubular magazine, a cartridge follower therein, an abutment in said magazine, a spring between said abutment and said follower, a pawl carried by said follower and adapted to project through said slot, and a sleeve surrounding said tubular member and slidable thereon, said sleeve having an aperture into which said pawl is adapted to project.
- 45 14. In a firearm, a slotted tubular magazine, a cartridge follower therein, an abutment in said magazine, a spring between said abutment and said follower, a pawl carried by said follower and adapted to project through said slot, a sleeve surrounding said tubular member and slidable thereon, means on said sleeve to engage said pawl, 85 and means to maintain said sleeve in either of two positions.
- 50 15. In a firearm, a slotted tubular magazine, a cartridge follower therein, an abutment in said magazine, a spring between said abutment and said follower, a pawl carried by said follower and adapted to project through said slot, a sleeve surrounding said tubular member and slidable thereon, said sleeve having an aperture into which 90 said pawl is adapted to project, and means to maintain said sleeve in either of two positions.
- 55 16. In a firearm, a slotted tubular magazine, a spring pressed cartridge follower therein, a pawl carried by said follower and adapted to project through said slot, a sleeve surrounding said tubular member and slid- 105 able thereon, means on said sleeve to engage said pawl, and a spring pressed plunger adapted to seat in either of two apertures in said sleeve.
- 60 17. In a firearm, a slotted tubular magazine, a spring pressed cartridge follower therein, a pawl carried by said follower and adapted to project through said slot, a sleeve surrounding said tubular member and slid- 110 able thereon, said sleeve having an aperture into which said pawl is adapted to project, and a spring pressed plunger adapted to seat in either of two apertures in said sleeve.
- 65 18. In a firearm, a barrel, a slotted tubular magazine, a plug in the end of said magazine, means to attach said plug to said barrel, a cartridge follower in said magazine, a spring interposed between said follower and plug, a pawl carried by said follower and adapted to project through said slot, a sleeve surrounding said tubular member and slid- 115 able thereon, said sleeve having an aperture 120
- 70 19. In a firearm, a slotted tubular magazine, a cartridge follower therein, an abutment in said magazine, a spring between said abutment and said follower, a pawl carried by said follower and adapted to project through said slot, a sleeve surrounding said tubular member and slid- 125 able thereon, said sleeve having an aperture 130

into which said pawl is adapted to project, and a spring pressed plunger adapted to seat in either of two apertures in said sleeve.

19. In a firearm, a receiver having an aperture in its front wall, a tubular magazine having one end projecting into said aperture, a breech-bolt having a guideway to receive the head of a cartridge, a pivoted

member on said breech-bolt adapted to engage the underside of said cartridge, and means to operate said pivoted member, the upper wall of said aperture being grooved to allow tilting of the cartridge.

In witness whereof, I hereunto affix my signature this 18th day of May 1923.

CARL G. SWEBILIUS.
